UNITED STATES PATENT OFFICE

94,932

DESIGN FOR A SUPPORTING FRAME

Lewis P. Weil, Oak Lane, Pa.

Application November 14, 1934, Serial No. 54,012

Term of patent 3½ years

To all whom it may concern:

Be it known that I, Lewis P. Weil, a citizen of the United States, residing in Oak Lane, in the county of Montgomery, State of Pennsylvania, have invented a new, original, and ornamental Design for a Supporting Frame, of which the following is a specification, reference being had to the accompanying drawing, forming part thereof.

Fig. 1 is a view in elevation of the article showing my design.

Fig. 2 is a plan view of same.

The supporting frame may be used in connection with table decorations, such as small glass globes to hold flowers, or it may be used in connection with vegetable or fruit displays.

It will be noted that the three ring formations are on different planes so that the objects supported thereby are also held in different planes or at different elevations.

I claim:—

The ornamental design for a supporting frame as shown and described.

LEWIS P. WEIL.
